US0D1021864S

(12) **United States Design Patent** (10) **Patent No.:** **US D1,021,864 S**
(45) **Date of Patent:** **** Apr. 9, 2024**

(54) **EARBUD**

(71) Applicant: **Zound Industries International AB**,
Stockholm (SE)

(72) Inventor: **Kenny Hugooh Wong**, Stockholm (SE)

(73) Assignee: **Zound Industries International AB**,
Stockholm (SE)

(**) Term: **15 Years**

(21) Appl. No.: **29/800,020**

(22) Filed: **Jul. 19, 2021**

(51) LOC (14) Cl. **14-01**

(52) U.S. Cl.

USPC **D14/223**

(58) **Field of Classification Search**

USPC D14/223, 205, 383, 384, 389; D13/108;
D24/106, 174; 128/864-866;

(57) **CLAIM**

The ornamental design for an earbud, as shown and described.

DESCRIPTION

FIG. 1 is a perspective view of an earbud showing the new design.

FIG. 2 is a front view thereof.

FIG. 3 is a back view thereof.

FIG. 4 is a left view thereof.

FIG. 5 is a right view thereof.

FIG. 6 is a bottom view thereof; and,

FIG. 7 is a top view thereof.

1 Claim, 4 Drawing Sheets
